ATTORNEYS.

UNITED STATES PATENT OFFICE.

RIA OLIVE ANDERSON, OF OAKLAND, CALIFORNIA, ASSIGNOR TO WESTERN CASKET CO., OF OAKLAND, CALIFORNIA, A CORPORATION.

DESIGN FOR A COMBINED CASKET AND LINING.

Application filed October 27, 1924. Serial No. 11,296. Term of patent 3½ years.

To all whom it may concern:

Be it known that RIA OLIVE ANDERSON, a citizen of the United States, residing at Oakland, in the county of Alameda and State of California, has invented certain new, original, and ornamental Design for Combined Casket and Lining, of which the following is a specification, reference being had to the accompanying drawing, forming part thereof.

The figure is a perspective view of a combined casket and lining, showing my new design.

I claim:

The ornamental design for a combined casket and lining, as shown.

In testimony whereof I affix my signature.

RIA OLIVE ANDERSON.
